UNITED STATES PATENT OFFICE

HIRAM B. ANDREWS, OF MELROSE, MASSACHUSETTS, ASSIGNOR OF ONE-HALF TO
JOSEPH B. SIMPSON, OF NEWTON, MASSACHUSETTS.

TAMPING IMPLEMENT.

981,517.

Specification of Letters Patent. Patented Jan. 10, 1911.

Application filed June 29, 1910. Serial No. 569,427.

To all whom it may concern:

Be it known that I, HIRAM B. ANDREWS, a citizen of the United States, and a resident of Melrose, in the county of Middlesex and 5 Commonwealth of Massachusetts, have invented an Improvement in Tamping Implements, of which the following description, in connection with the accompanying drawings, is a specification, like letters on the 10 drawings representing like parts.

This invention aims to provide an improved implement for tamping concrete and the like.

According to the present practice, where 15 a concrete floor or bottom is required to have a smoothly finished top surface the main body or layer of concrete is first laid with a mixture of stone or other aggregate, sand, cement and water, in proper proportions, and then after this main or foundation layer has partially or wholly set, there 20 is spread thereon a surface coating of sand, cement and water, and richer in cement than the main or principal layer, which finish 25 coating is smoothed off to give the required smoothness of finish to the top or exposed surface. This procedure involves excessive cost because of the larger percentage of cement required in the surface of finish coating, as compared with what is required for 30 strength and body alone as in the principal layer, and also because of the additional labor involved in making up two batches of mixture and separately laying the same.

35 My invention comprehends a tamping implement of such construction that the stones forming a part of the principal layer of concrete may be so displaced as to cause sufficient sand, cement and water to come to the 40 surface, to permit of the necessary smoothing of the layer to give the required finish at the surface without the necessity of applying a special layer, richer in cement, for that purpose alone.

45 The accompanying drawing illustrates a preferred embodiment of my invention, in which—

Figure 1 is a side view of the implement; and Fig. 2, a face view thereof.

50 Referring to the drawing, and the particular embodiment of my invention there shown, the implement comprises a head 1, provided with a suitable socket 2 for a handle 3, or a suitable handle may be provided 55 in any other desired manner.

The head may be of any convenient dimensions, shape and material, although metal is preferred, the same being provided at its active face with a plurality of tamping projections 4, conveniently and preferably pyramidal in shape and quite closely arranged throughout the entire area of the face of said head. The apices of these pyramidal projections are preferably pointed, so as readily to penetrate the concrete mass and 60 permit the projections to enter between the stones or stony particles rather than drive them all bodily downward, as would be the tendency were the projections to have blunted or squared ends. Further to promote the 65 entrance of these projections between the stones of the concrete, the angular pitch at the side faces of the same is preferably about as shown, contrasted with a very low and broad based pyramidal or conical form, 70 and the bases of adjacent pyramids are shown as preferably connected by easy fillets 75 5, to prevent, so far as possible, particles of stone from becoming wedged between the contracting surfaces at or near the bases of 80 the projections. Obviously, a conical or other equivalent shape of projection might be used, although the pyramidal, so far as my present experience goes, furnishes the most 85 satisfactory as well as the most economical form to maintain.

In use, after the layer of concrete has been spread and roughly leveled with the customary straight edge, the workman proceeds to tamp the same from the top surface, the 90 pyramidal projections of the tamping implement serving to displace and somewhat depress more or less of the stone contained in the layer, with the result that the freer sand, cement and water contained in the mass, together with more or less of the finer particles 95 of the stone, are forced or permitted to rise to the surface, leaving the latter in such condition that it may be smoothed off with a float or trowel substantially as the separately applied finish layer is smoothed off or 100 finished, according to the present practice. So smooth is the surface so obtained that I have found it unnecessary to employ any 105 separately applied finish layer.

Having described one embodiment of my invention, what I claim and desire to secure by Letters Patent is:

1. As a new article of manufacture, a tamping implement provided at its active 110

face with a plurality of tapering tamping projections, the bases of which are in contact with each other.

2. As a new article of manufacture, a
5 tamping implement provided at its active face with a plurality of tapering tamping projections, joined one to another at their bases by curved connecting surfaces.

In testimony whereof, I have signed my name to this specification, in the presence of 10 two subscribing witnesses.

HIRAM B. ANDREWS.
